UNITED STATES PATENT OFFICE.

HENRY H. DOERING, OF CHICAGO, ILLINOIS.

BUTTER-PRINT MACHINE.

1,403,673.

Specification of Letters Patent. Patented Jan. 17, 1922.

Application filed April 30, 1919. Serial No. 293,712.

To all whom it may concern:

Be it known that I, HENRY H. DOERING, a citizen of the United States, and a resident of Chicago, in the county of Cook and State 5 of Illinois, have invented certain new and useful Improvements in Butter-Print Machines, of which the following is a description, reference being had to the accompanying drawings, which form a part of my 10 specification.

My invention relates to a butter print or molding machine which will be positive or self-feeding when the hopper or receiving trough of the machine has been charged 15 with the bulk or unmolded butter; a machine wherein the compactness of the prints or molded butter will be automatically determined by the construction and operation of the mechanism; while at the same time 20 the size of the molds or prints may be readily controlled and determined by the simple adjustment of the head or throat portion of the machine at the delivery end thereof.

One object of my invention is to provide 25 a machine of the class referred to wherein the feeding of the butter will be determined and controlled by suitable rotatably mounted means, preferably in the nature of worms arranged in parallel relation and with oppositely disposed spiral or threads which 30 will induce a positive feed of the butter from the charging to the delivery end of the machine; my invention also contemplating a construction wherein the feeding mechanism or worms may be readily removed 35 without the necessity of dismantling the entire construction; the operation being accomplished by merely removing the head or discharging throat portion of the machine 40 through the removal of a few bolts or nuts.

Another object of my invention is to provide a machine wherein the molded butter will be delivered to a print-forming mechanism or element and thence delivered to a 45 conveying table or traveling element to be wrapped and delivered; all of said mechanisms being controlled and operated by a single power unit which may be thrown into operative relation with the mechanism at 50 the will of the operator.

The objects and advantages of my invention will be more fully comprehended from the following detailed description of the drawings, wherein:—

55 Figure 1 is a top plan view of my im-

proved butter molding and printing machine.

Figure 2 is a side elevation of the construction shown in Figure 1.

Figure 3 is a longitudinal sectional view 60 of the molding portion of the machine, taken substantially on the line 3—3 of Figure 2, and showing the butter feeding mechanism.

Figure 4 is a longitudinal sectional view, 65 taken on the line 4—4 of Figure 3 looking in the direction of the arrows.

Figure 5 is a cross sectional view, taken on the line 5—5 of Figure 2.

Figure 6 is a detail view partly in section of the print-forming or cutting mechanism. 70

Figure 7 is a sectional view of the mechanism shown in Figure 6, taken substantially on the line 7—7.

The construction shown in the drawings 75 I believe to be one of the simplest and best forms of my invention, but the invention may have expression in somewhat different mechanical form and still embody the spirit of the invention which is specifically described in the following specification and outlined in the appended claims.

In the particular embodiment of the invention as set forth in the drawings, it comprises the butter-forming or molding unit; 85 the print-forming or cutting mechanism and the conveying mechanism; the main features of the invention, however, being embodied in the butter-molding and print-forming mechanisms. These mechanisms 90 comprise a suitable frame or supporting structure as shown at 10, which may be of metal or other suitable material, on which is mounted the molding mechanism which consists, preferably of a pair of blocks or 95 members 11 and 12 of suitable thickness and width, as well as length, and preferably of wood so as not to affect the butter in its passage through the machine. The blocks or members 11 and 12 are each provided 100 with semi-cylindrical cores or grooves; with the grooves of the two members arranged so as to register with each other when the blocks or members 11 and 12 are arranged in superposed relation, as more clearly 105 shown in Figure 5.

The upper member or block 11 is of less length than the lower member 12, as shown in Figure 4, in order to provide for the charging trough or hopper shown at 13. 110

- The trough or hopper 13 is preferably provided with a sloping ledge as at 14, see Figures 2 and 5, in order that a considerable quantity of bulk butter may be loaded into the trough or hopper and be induced to move toward the opening or chute of the trough which communicates with the ends of the circular passages formed in the blocks or members 11 and 12 by the registering 5 semi-circular grooves previously referred to and as shown in Figures 4 and 5.
- The forward or trough end of the upper member 11 is preferably provided with a beveled block or end 11^a arranged intermediate of the main portion of member 11 and the chute portion of trough 13. The block or end 11^a is shown beveled on its under surface with a predetermined taper so as to gradually restrict the receiving end of the 10 passage through the machine; the block or end 11^a being also preferably given a slightly less bevel or inclination at the point 11^b where it connects with the main portion of the passage. I have found in practice 15 that unless a proper taper is provided at the receiving end of the passage through the machine, proper self-feeding of the butter in equal quantities will not be obtained; and the particular taper shown in the drawings 20 30 I find produces the best results.
- Rotatably mounted in the passages in the main or body portion formed by members 11 and 12 are a pair of worms or screws 15 and 16; the spirals or threads of the worms being intended to be in contact with the sides of the passages through the blocks or members 11 and 12, as shown in Figures 3 and 5; the two passages, however, being united at a 35 point substantially parallel with the longitudinal axes of said passages, as shown at 17 in Figure 5. With the worms or screws supported throughout their lengths in the blocks or members 11 and 12 as described, it is merely necessary to provide one end of 40 each screw or worm with a trunnion, as shown at 18 and 19, respectively in Figure 3, to enable operation of the worms; and these trunnions are shown preferably squared or shouldered so as to register and fit into the 45 square apertured ferrules or collars 20, 20 secured to the ends of the driven shafts 21, 21. The shafts 21, 21 have suitable bearings in the supporting standard or pillow-blocks 22, and the ends of the shafts 21 are provided 50 with meshing gears as at 23, 23. The one shaft 22 is disposed beyond the gear 23 and is provided with suitable clutch mechanism, as shown at 24, which is operated by means of lever 25; the clutch being normally 55 held out of clutching relation by means of a spring 26. The lower end of lever 25 is pivotally connected to a link 27 which in turn is pivotally connected to a bell-crank lever 28 suitably mounted on the frame of 60 the machine and controlled by means of foot 65

treadle 29 which is disposed at a point in proximity to the delivery end of the molding portion of the machine.

As more clearly shown in Figure 3, the spirals or threads of the screws or worms 70 are oppositely disposed; that is, screw or worm 15 is provided with a left hand thread or spiral, while worm or screw 16 is provided with a right hand thread or spiral.

Worm or screw 16, which is driven by any 75 suitable source of power, is intended to revolve in the direction of the arrow shown in Figure 3, thus causing worm or screw 15, by reason of the gear connections between the worms, to rotate in the opposite direction as indicated by the arrow in Figure 3. With this mechanism, the butter is positively fed from the hopper end of the machine toward the throat or discharging head thereof.

The head or discharging throat is formed 80 by means of suitable members 30 and 31 which are preferably bolted to the end of blocks or members 11 and 12 by means of the rods 32, 32 which may be disposed through members 11 and 12 as shown in Fig-

ure 3; the bolts at the same time clamping the rear end wall 33 in place. The rear end wall 33 is provided with suitable openings 90 for the trunnions 18 and 19 of the worms 15 and 16, respectively, and therefore also pro-

vides suitable bearings for the trunnions. The head members 30 and 31 are beveled on their inner faces or arranged at a suitable angle to the ends of members 11 and 12 and disposed toward each other so as to provide 100

the converging passage, as shown at 34 in Figures 3 and 4. The passage 34 terminates in a throat or discharge orifice 35, which is 105 preferably rectangular in cross-section as shown, to discharge the butter in slabs or strips of similar configuration, in cross-section; the dimensions or size of the strip or slab being controlled by adjustment of

throat-member 36 which is held in place by means of a bolt 37 shown extending in a vertical manner through the head and through an elongated slot 38 formed in throat-member 36. This construction permits the 110

throat-member 36 to be moved in a horizontal direction toward or away from the 115 opposite or stationary wall of the throat as is readily apparent from the illustration in Figure 3. The adjustment of throat-member 36 is controlled by means of rod 39, the inner end whereof is provided with a screw or worm as at 40 which meshes with a rack 41 secured within a suitable groove in the side of throat-member 36. The rod 39 ex-

tends through to the head exterior as shown in Figures 1 and 3 and is provided with a 120 suitable hand-wheel 42; while longitudinal movement of rod 39 and its worm 40 is prevented by means of the channel member or bracket 43 arranged in a suitable socket or

groove in head-member 30, with the sides of 125

the machine and controlled by means of foot 130

- the bracket or channel member engaging opposite sides of the worm 40 and thereby maintaining the latter and rod 39 against movement in a longitudinal direction, yet 5 at the same time permitting free rotation thereof. It is evident from the construction shown and described, that upon releasing a clamping nut 44, secured on the end of bolt 37, throat-member 36 will be released so as 10 to permit lateral movement thereof upon rotation of rod 39, whereby the width of the discharging strip of butter will be regulated. The formed butter passing through throat 35 is discharged upon a series of freely rotating rollers 45 which are preferably provided with trunnions as at 46 in Figure 6 arranged in sockets provided in a suitable frame as at 47 mounted on the table or upper part of the standard 10. 20 Pivots mounted on the frame which supports the rollers 45, so as to be disposed in a direction transversely of the path of the formed butter, is a print-forming device in the nature of a frame, composed preferably of bowed or arcuate formed T-irons 48, pivotally secured at one end as shown at 49 to the frame of the machine so as to permit the device to swing in a vertical direction as shown in dotted lines in Figure 6. 30 The frame of the device is preferably shown as consisting of two arcuate formed T-irons, see Figures 1 and 2, rigidly secured together by means of a suitable handle 50 whereby the frame may be controlled by the operator. 35 I prefer to employ the T-iron formation, for the purpose of strength and rigidity; and the ends of the irons or bowed members are secured to the horizontally arranged angle members 51, 51, to which the print-cutting 40 wires or elements 52 are secured. A suitable number of wires may be employed, as for example four, as shown in Figure 1, whereby a plurality of prints will be cut with one operation of the print-forming device. The 45 print-forming or cutting elements preferably consist of wires having their ends secured to eye-bolts 53, 53 which pass through apertures in the angle members or frame portions 51, with their outer ends provided 50 with suitable thumb or butterfly nuts, as at 54, see Figure 6. With this construction, the wire may be placed under proper tension to effectively cut the prints; while at the same time they may be readily replaced upon 55 unscrewing the thumb-nuts 54. The handle 50 is secured adjacent the free end of the print-forming frame and upon raising and lowering the frame at proper moments it is evident that the formed butter discharging 60 onto the free running rollers 45 will be cut into prints of predetermined size of uniform dimensions. The size, as well as the weight of the prints of the butter may be regulated and determined by the length of the screws 65 or worms and their speed of rotation, in con- junction with the regulation or size of the throat. The butter when supplied to the machine in proper quantities is subjected to a predetermined pressure by the worms or screws and formation of the passage, so that 70 the formed butter will be of uniform compactness when discharged through the throat 35; and the distance between the respective cutting elements or wires 52 will determine the size of the prints cut thereby, so that 75 prints of predetermined size and weight can be produced. The formed prints will be caused to move across the rollers 45, by the butter discharging from the throat, and thence forced onto a conveying table or continuous belt, as shown at 55, in Figures 1 and 2, which is shown disposed about a suitable pulley 56, adapted to receive its power by suitable belt or gearing from a line shaft 57, which in turn receives its power by means 80 of belt or gearing, as shown at 58, from the driven shaft which imparts power to the worms or screws; the power for the conveying table being transmitted from the driven shaft, however, at a point forward of the 85 clutch 24 in order that the conveying table may have continuous operation. As is usual in the operation of apparatus of the class herein referred to, the conveying table or belt 55 is adapted to convey the prints to a 90 stationary table or platform, disposed along the path of the conveying member 55, where the butter or prints are wrapped by an operator and then placed in suitable cartons. 95 In the particular construction shown in the 100 drawings, the shaft provided with the clutch 24 is suitably mounted in bearing blocks or pillows 59 and has its ends provided with a gear 60 which meshes with a pinion 61 secured to a short or stub-shaft provided with 105 pulley 62. With this construction it is evident that power is transmitted to pulley 62 by means of a suitable belt and through the medium of gear 61 to gear 60, so that when clutch 24 is actuated so as to throw shaft of 110 worm 16 into operative relation with gear 60, the gear 23 thereon will also actuate the worm 15 and induce the two worms to rotate toward each other and at uniform speed, thus causing the bulk butter to be positively fed from the hopper end of the machine toward the print-forming end thereof. With the arrangement of gearing just described, it is apparent that operation of clutch 24 will throw both worms out of operative relation with the power-imparting mechanism. 115
- What I claim is:
1. In a machine of the class described, a main portion provided with a pair of parallelly arranged, longitudinally disposed cylindrical passages arranged in juxtaposition, said passages being arranged in communication with each other throughout their lengths substantially in the plane of their longitudinal axes, a charging hopper ar-

- ranged at one end of said passages, the upper walls of the main portion intermediate of the hopper and said passages being flared upwardly toward said hopper with the flare 5 adjacent to the passages made with a lesser inclination or flare so as to gradually restrict the passage for the butter from the hopper to the longitudinal passages, the end of the main portion at the opposite ends of 10 the longitudinal passages being formed with converging walls to provide a gradually restricted discharge-end, common to both passages, laterally adjustable means whereby the size of the discharge orifices may be controlled, and revoluble worms, having oppositely disposed spirals throughout their lengths, arranged in said passages and adapted to rotate in unison toward each other and in contact with the sides of the 15 20 passages whereby the material is compressed between the adjacent worms and fed from end to end through said passages, in combination with a vertically swinging frame having horizontally disposed portions arranged in spaced relation, a plurality of cutting wires disposed intermediate of said horizontally disposed portions, said swinging frame with said cutting wires being adapted to be swung downward across the 25 30 path of the butter discharged by said worms, and regulable means secured to the horizontally disposed portions whereby said wires are secured in place and their tension controlled.
- 35 2. A machine of the class described, comprising a main portion composed of a pair of blocks each provided with parallelly arranged semi-cylindrical grooves, the blocks being in superposed relation, with the 40 grooves registering with each other, to provide cylindrical passages lengthwise of the blocks, the grooves in both blocks being formed to provide a communicating passage between the cylindrical passages at a 45 point substantially in the same horizontal plane as the axes of said passages, a worm in each cylindrical passage, with the spirals or threads of the two worms disposed in opposite directions, the spirals of said worms being of diameter substantially equal to the inside diameter of the cylindrical passages and each provided at one end with a trun-
- nion, an end member removably secured to one end of the blocks to provide bearings for said trunnions, a hopper disposed on the uppermost block and communicating with said cylindrical passages by means of a forwardly tapering throat, a head removably secured to the opposite ends of said blocks and formed to provide a single, gradually converging outlet, a throat member adjustably secured to said head, regulable means whereby said throat member may be adjusted and the size of material discharging therethrough regulated, in combination with a vertically swinging frame provided with a plurality of cutting wires arranged in parallel spaced relation, the frame and wires being adapted to be swung downwardly across the material discharging through said throat. 55 60 65 70
3. A machine of the class described, comprising a main portion provided with a pair of parallelly arranged cylindrical passages communicating with each other throughout their lengths at their intersecting circumferences, a worm mounted in each cylindrical passage, the spirals of the two worms being oppositely disposed and of diameter substantially equal to the inside diameter of said cylindrical passages, means whereby the worms are rotated in unison toward each other, foot operated mechanism for controlling said last mentioned means, an end member removably secured to one end of said 75 80 85 90 95 98 passages to provide bearings for said worms, a tapered head secured to the opposite ends and arranged to provide a single converging outlet, a portion of said head being laterally adjustable to regulate the discharge orifice of said head, in combination with a vertically swinging frame adapted to swing downwardly across the path of the discharging butter and adapted to cut the same into a plurality of prints of predetermined and equal dimensions, and conveying means disposed at the discharge orifice of said head for receiving the butter prints, said conveying means being operable by the worm operating means. 95
